Louis O. French

UNITED STATES PATENT OFFICE

2,598,528

FUEL INJECTION APPARATUS

Louis O. French, Milwaukee, Wis.

Application December 20, 1948, Serial No. 66,279

5 Claims. (Cl. 103—41)

1

The invention relates to fuel injectors for internal combustion engines and more particularly to those of the combined fuel pump and sprayer type generally known as unit injectors.

In unit injectors of known construction the fuel pump plunger is operated by a cam operated lever from the engine. Cam drives have distinct limitations because they generally necessitate using as a minimum such degrees of crank angle rotation as to prevent all the fuel being injected into the engine during the period of ignition lag with the result that the fuel air ratio is not as good as it should be since the last portion of the fuel charge may not mix with its required air component resulting in incomplete combustion. Usually injection with cam operated injectors occurs within twenty to fifteen degrees of engine crank angle whereas better fuel mixing and economy could be obtained if the injection period were cut down to half or preferably less than half of this figure. Furthermore, with cam operated fuel plungers the rate or speed of injection varies with engine speed so that injection efficiency decreases with a decrease in engine speed. The above objections can be overcome where the fuel plunger is operated by a hydraulic actuator, and one object of this invention is to provide a hydraulically operated plunger operating piston operated by an external source of hydraulic pressure fluid at any desired pressure suitable for rapid operation of the fuel pump plunger to deliver its fuel charge at any desired injection pressure and at a rate independent of engine speed, the operation of said operating piston being controlled by a timing valve operable in cyclic synchronism with the engine.

A further object of the invention is to provide a fuel pump having a double acting hydraulic motor actuator whose operating piston is angularly adjustable from one end of the motor to vary the metering effect of the pump, the arrangement avoiding the necessity for a stuffing box or other special seal between the high and lower pressure cylinders or barrels.

A further object of the invention is to provide a fuel pump whose pump plunger is operated by a hydraulic motor actuator whose operation is controlled by an electromagnetically operated timing valve whose control switch may be readily applied to any engine and may be used to control a plurality of pumps for a single engine cylinder as in the case of opposed piston engines.

The invention further consists in the several features hereinafter set forth and more particu-

2

larly defined by claims at the conclusion hereof.

In the drawings:

Fig. 1 is a vertical sectional view of a fuel injection apparatus embodying the invention;

5 Fig. 2 is a detailed vertical sectional view taken on the line 2—2 of Fig. 1;

Fig. 3 is a detailed sectional view showing certain modifications;

10 Fig. 4 is a diagrammatic view of a fuel injection system embodying the invention;

Fig. 4A is a vertical sectional view through a combined accumulator and relief valve that may be used in the injection system;

15 Fig. 5 is a view similar to Fig. 1 showing certain modifications, parts being broken away.

In the drawings, the numeral 6 designates generally a unit injector or combined fuel pump and sprayer mounted in the bore 7 of the head or cylinder 8 of an internal combustion engine and suitably secured thereto by clamping means (not shown). In each instance the injector includes a housing or casing 9 in which a fuel pump barrel 10 is mounted and secured by a sleeve nut 11, a high pressure pump plunger 12 working in said barrel and controlling fuel inlet ports 13, a discharge valve assembly and a nozzle or discharge member 14 clamped in assembled relation with the barrel by a sleeve nut 15. Fuel from a suitable pressure source is circulated through the housing by way of port 16, vertical groove 17 and annular groove 18 in the barrel connected with said ports 13, vertical groove 19 in the barrel and port 20.

20 The discharge valve assembly may comprise any suitable check valve to control the discharge from the pump chamber 21. As shown, a needle check valve 22 slidably mounted in a sleeve casing 23 is normally urged into contact with the apertured seat of a seat member 24 by a spring 25.

25 The discharge member 14 may be of any suitable construction provided with any suitable nozzle or valve controlled nozzle and as shown has a discharge passage 26 provided with spray orifices 27.

30 The discharge member 14 may be of any suitable construction provided with any suitable nozzle or valve controlled nozzle and as shown has a discharge passage 26 provided with spray orifices 27.

35 In both forms of the invention the pump plunger 12 is moved outwardly on its filling stroke and inwardly on its fuel injection stroke by a hydraulic motor actuator including a cylinder 28 and a piston 29 direct connected to said plunger in self-centering relation therewith, the cylinder 28 being formed integral with or bolted to the upper end of the housing 9. As shown cylinder 28 is bolted to said housing and has a fluid-tight connection therewith provided by a 40 suitable sealing ring 30 and has a bore 31 co-

50

axial with the plunger 12 and of greater diameter. A cap or top 32 is secured by screws 33 to the upper end of the cylinder with a fluid-tight connection provided by a sealing ring 34.

A spring 35 interposed between the housing and the piston 29 acts to overbalance the weights of the piston 29 and plunger 12 and tends to move them outwardly.

In Fig. 1 the self-centering direct connection of the plunger 12 and the piston 29 is provided by a nut 36 in threaded engagement with said piston and forming therewith a plunger head retaining pocket having side clearance for said head and plunger shank.

In Fig. 5 since the plunger 12 is to be angularly adjusted through the angular adjustment of the piston 29 the self-centering direct connection between the plunger 12 and the piston 29 comprises the nut 36 and an Oldham or universal coupling comprising a circular coupling plate 37 having diametrically extending ribs 38 and 39 on opposite sides thereof and disposed at right angles to each other, the rib 38 slidably mounted in a groove 40 formed in the piston 29 and the rib 39 slidably mounted in a groove formed in the head of the plunger, the plunger having side clearance in its mounting pocket.

Referring to Fig. 1, the cylinder 28 is provided with ports 41, 42, 43 and 44 communicating with the bore 31, a passage 45 connecting ports 43 and 44, a valve bore 46 connected with the port 41 and passages 47 and 48 and with spaced pressure fluid supply ports 49 and 50 connected to a supply port 51. The lower portion of the piston 29 is provided with a notch forming control edges 52 and 53 which cooperate with the relief port 43 whereby angular adjustment of said piston relative to said relief port will cause said control edges to cut off communication between the checking fluid chamber 54 in the lower end of the cylinder 28 and said relief port sooner or later in the inward movement of said piston to provide a variable hydraulic stop so that both the piston 29 and the plunger 10 will have their stroke varied, thus varying the amount of fuel delivered to the engine by the injector.

Referring to Fig. 5, the cylinder 28 is provided with ports 55 and 56 communicating with the bore 31 above and below the piston and with a valve bore 57 with which drain ports 58 and 59 and a pressure fluid supply port 60 also communicate, said piston 29 and plunger 12 being given a constant stroke by the hydraulic motor actuator. For metering the fuel the plunger 12 has a recessed portion 61 providing a control edge 62 and a slot 63 extending from said recess to the front end of said plunger, said control edge cooperating with one of the ports 13 whereby angular displacement of said control edge relative to said port 13 will by-pass fuel from the pump chamber 21 sooner or later and thus vary the amount of fuel delivered by the injector to the engine.

Thus in both instances metering is effected through an angular adjustment of the motor piston 29. In Fig. 1 said piston 29 acts to adjust the stroke of plunger 12 to vary the fuel charge while in Fig. 5 the angular adjustment of the constant stroke piston 29 and its associated plunger 12 acts to vary the amount of fuel by-passed from the high pressure pump chamber to vary the fuel charge.

In each instance for angularly adjusting the piston 29, a rod or key 64 mounted in the outer end thereof extends across a cavity 65 therein

and slidably works in a key slot 66 formed in the head 67 of a metering control member 68 extending into said cavity. Member 68 is rotatably mounted in the cap 32 in sealed relation therewith by forming said member as a valve having its head 67 seating on a valve seat 69 in said cap and its stem 70 working in a bore 71 in said cap, said member being normally held to its seat by a spring 72 interposed between said cap and a washer 73 secured to said stem which also carries an operating handle 74 for manual or governor control. Stem 70 may be provided with grooves 75 so that the outer end of the cylinder may be purged of air by pushing inwardly on the valve to unseat it and thus permit ready priming of this part of the hydraulic system.

The piston 29 has an annular groove 76 which in Fig. 1 is connected by one or more ports 77 with the upper end of the chamber 54 and registering in the outer position of said piston with the exhaust port 44 so that in this position of said piston any air that might be entrained in the hydraulic actuating liquid will be free to escape and thus the lower end of the cylinder 29 will be self-purging.

For operating the hydraulic motor actuator means are provided for supplying hydraulic fluid thereto at any desired pressure. Referring to Fig. 4, this means includes a liquid supply tank T for either a lubricant or fuel connected by piping including a strainer S to a motor or engine driven pump P preferably of the constant displacement type though other types may be used, said pump delivering to a standpipe SP connected by branch connections B to supply ports for the injectors I and connected by return piping R to the tank T, a pressure relief valve PR being mounted in a pipe BB connecting with the pipes SP and R. The relief valve PR may be set to deliver the operating liquid to the injector operating motors at pressures of five hundred to a thousand pounds per square inch or any desired pressure and the ratio of the areas of the fuel plunger 12 and the piston 29 may be 1 to 10 or 15, for example, depending upon the fuel injection pressure desired. The rate of injection will depend upon the supply pressures and the areas of the ports in the motor cylinder. For best results the rate of injection should be such as to inject the fuel charge into the engine within the period known as ignition lag and the pressure should be high, for example, 10,000 to 15,000 p.s.i.

The flow of pressure fluid to and from the hydraulic motor actuator is in each instance controlled by a piston valve. In Fig. 1 the piston valve 78 is slidably mounted in the bore 46 and is provided with annular grooves forming lands 79, 80 and 81 and is normally urged in one direction by a spring 82 interposed between its exposed head 83 and a stop plate 84, and when engaged with said stop as shown in Fig. 1, the port 49 is lapped by the land 79, the port 41 is connected through the upper groove in the valve with the passage 47 shown diagrammatically as extending around the bore 31 and connecting with the exhaust 44, the port 50 is connected through the lower groove in the valve with the passage 48 including port 42 which conducts pressure fluid from the supply port 51 into the chamber 54 and acting on the lower face of the piston 29 quickly raises it and the plunger 10 to the position shown in which the fluid is then free to pass out through the port 43, 45 and 44 to the return pipe.

When the valve 78 is shifted so that the land 81 laps the passage 48 and port 50 and the land

80 laps the passage 47 and the land 79 moves out of lapping relation with the port 49 so that this port and port 41 are connected together by the upper groove of the valve, then the pressure fluid flows through port 41 to the upper end of the cylinder 28 moving the piston 29 and the plunger 12 downwardly against the pressure of the spring 35 and puts pressure on the fuel in the pump chamber 21 until the loading of spring 25 is overcome and valve 22 then opens allowing fuel to pass through member 14 and its orifices 27 into the combustion chamber C of the engine. When, on this downward movement of the piston 29, the control edge 52 laps the relief port 43, hydraulic fluid is trapped in the chamber 54 and forms a hydraulic stop preventing further inward movement of said piston and the plunger 12 and injection stops. When the valve 78 is again shifted back, the hydraulic fluid, as previously described, together with the spring 35 moves the piston 29 and plunger 12 outwardly until the ports 13 are again uncovered to allow a new charge of fuel to enter the fuel pump chamber 21. Thus the fluid pressure actuator above described functions as a variable stroke double acting hydraulic motor to move the plunger 12.

In Fig. 5 a piston valve 85 works in the valve bore 57 and is provided with annular grooves forming lands 86, 87 and 88 which may be moved in one direction by a spring as in the first described construction. When said valve is in the position shown, fluid from the upper end of the bore 31 is free to pass through ports 55 and 53 to the return while pressure fluid supplied through port 60 passes by way of port 56 to the lower end of the bore 31 acting on the piston and its associated plunger to raise the same to the position shown. When on the downward movement of this valve 85 the land 86 moves into lapping relation with the port 58, the land 88 out of lapping relation with the port 59 and the land 87 to a position below the port 60, then the pressure fluid will flow from the port 60 to the port 55 moving the piston 29 and plunger 12 downwardly while fluid is exhausted from below said piston through the port 56 and port 59 to the return.

In Fig. 1 I have shown a manually adjustable throttle valve 89 connected with the exhaust port 44 to vary the rate of flow of liquid from the lower end of the cylinder so that the rate of injection may be varied, if desired. This same valve 89 may be connected with the drain or return port 59 in Fig. 5 for a similar purpose.

When the engine is provided with an overhead cam shaft or valve shaft 90, the valve 78 may be operated in cyclic synchronism with the engine either directly by a suitable cam 91 on said shaft or as shown in Fig. 3 by a pivoted lever 92 operated by the cam 91 on said shaft and acting on the head 83. The valve 85 may be similarly actuated, but since this valve is in a normally raised position when the injector is not operating, the cam 91 will have a depressed portion substituted for its nose 93 shown in Fig. 3. Where it is not convenient to use such a cam shaft drive or the engine does not have or need an auxiliary shaft adjacent the injectors as, for example, in many two cycle engine designs, then the means for operating the valve 78 or 85 is preferably an electromagnet such as a plunger type solenoid electromagnet E of the iron clad type shown in Fig. 1 including the energizing coil 94, the magnetic stop 95 provided with an anti-freeze stop projection 96 and the plunger 97, which may form an exten-

sion of the valve 78, and a control circuit for said magnet including an engine operated switch or timer 98.

The control circuit includes a conductor 99 connecting one side of the coil 94 to one terminal of a battery 100 or other suitable source of direct current and a conductor 101 connecting the other terminal of said battery with a contact 102 of the switch 98. The other side of the coil 94 is grounded at 103. The switch includes an engine driven rotary switch contact 104 connected to ground which cooperates with the suitably insulated contact 102 to close the circuit through the connections above described to energize the coil 94 at such a time in the engine's cycle as will insure movement of the valve 78 with its plunger 97 against the action of the spring 82 to its upper or fuel injection position so that injection may start, for example, within ten to one degree of crank angle before top dead center, the contact 102 being angularly adjustable to accommodate for the electrical lag in the electromagnet and in order that this electrical lag will not interfere with the operation under varying engine speeds, the switch 98 is preferably of the type having a built-in automatic or speed controlled angular advance for contact 104, as for example, a governor controlled timing switch of the type shown in my prior U. S. Patent No. 1,705,665, dated March 19, 1929. Where more than one injector is used per cylinder, their valve operating electromagnets are connected in parallel with the control switch. The valve 85 may also be solenoid controlled, and with the form shown in Fig. 5 using the solenoid shown in Fig. 1 the control switch 98 would be closed during the time the valve 85 is in the position shown and the injector is not operating.

To decrease the capacity of the pump P the hydraulic operating system may be provided with an accumulator to build up a supply of pressure fluid during the non-working period of the injector, and in Fig. 4A I have shown an accumulator suitable for this purpose and also functioning as a relief valve. This device includes a casing 105 having a bore 106 provided at its lower end with an inlet 107 and outlet 108 which may form part of the standpipe SP and provided with a relief port 109 and a port 110 connected with the port 109. An accumulator and valve piston 111 having a slotted lower end works in the bore 106 and is urged by the hydraulic fluid against a pressure determining spring 112 whose tension may be adjusted by the adjusting screw 113 having threaded engagement with the casing cap 114 and bearing on a spring seat member 115 slidably mounted in sealed relation with a bore 116 in said cap. With this arrangement during non-working periods of the injector or injectors the pressure acting on the piston 111 moves it upwardly against the loading of the spring 112 until the lower slotted end of the piston passes the relief port 109 at which time fluid may then flow through said relief port to the return pipe R with which it is connected. During the time the valve 78 or 85 is moved to cause the injection stroke of the piston 29 and plunger 12, the pressure built up by the accumulator piston is utilized to aid in producing a quick movement of said piston and plunger.

While the valves 78 and 85 are shown as built into the cylinder, they may if desired be separate units connected by suitable piping to the motor cylinder as will be readily understood.

While lubricant may be used for the operating

fluid, where fuel oil is used in the engine, it may be used as the pressure operating fluid in which event the fuel supply passage 16 in the injector may be connected in circuit with the exhaust port 44 or 59 or the outlet from valve 89 when associated with either of said ports and from a part of the return piping and the piping connections thus simplified.

The above construction permits introduction of fuel at any desired pressure and at any desired rate, which rate is independent of engine speed so that injection efficiency will not decrease with engine speed and the period of injection may be made so short that with good combustion chamber design the air-fuel ratio will more nearly approach the limit of saturation, that is to say, a theoretical fuel air mixture containing no excess air, with a resulting increase in engine efficiency.

I desire it to be understood that this invention is not to be limited to any particular form or arrangement of parts except in so far as such limitations are included in the claims.

What I claim as my invention is:

1. In a fuel injection apparatus having a high pressure plunger fuel pump, the combination of a hydraulic operated actuating piston connected to the plunger of said pump, an exterior source of hydraulic pressure liquid at a predetermined pressure lower than the delivery pressure of said pump for operating said actuating piston, valve means operable in cyclic synchronism with the engine for controlling the passage of said hydraulic liquid to and from said actuating piston, valve means for controlling the quantity of fuel delivered by said pump, and externally adjustable means for controlling said valve means including means for angularly adjusting said actuating piston.

2. In a fuel injection apparatus for internal combustion engines having a plunger fuel pump, the combination of a hydraulic motor mounted on said pump including a cylinder and an operating piston working in said cylinder and direct connected to the plunger of said pump, the inner end of said cylinder and the piston cooperating to form a checking fluid chamber, said cylinder having a relief port communicating with said chamber, said piston having a control edge cooperating with said relief port to trap liquid in said chamber, means for angularly adjusting said piston to vary the position of said control edge relative to said relief port to vary the stroke of said piston and said plunger, means for supplying hydraulic operating liquid to said cylinder at a predetermined pressure, and valve means operable in cyclic synchronism with the engine for controlling the passage of said hydraulic liquid to and from said cylinder.

3. In a fuel injection apparatus for internal combustion engines having a plunger fuel pump, the combination of a hydraulic motor mounted on said pump including a cylinder and an operating piston working in said cylinder and direct connected to the plunger of said pump for reciprocating and rotary movement therewith, said pump plunger having a control edge, said pump having a barrel provided with a relief port cooperating with said control edge to vary the fuel charge delivered by said pump, means for angularly adjusting both said operating piston and said plunger to vary the position of said relief port relative to said control edge including a rotatable control member mounted in said cylinder and having an exteriorly disposed operating connection, means for supplying hydraulic operating liquid to said cylinder at a predetermined pressure, and valve means operable in cyclic synchronism with the engine for controlling the passage of said hydraulic liquid to and from said cylinder.

4. In a fuel injection apparatus for internal combustion engines having a plunger fuel pump, the combination of a hydraulic motor actuator for the plunger of said pump, an exterior source of hydraulic pressure liquid at a predetermined pressure for operating said actuator, a piston valve for controlling the passage of said hydraulic liquid to and from said actuator, an electromagnet for controlling said valve, and a control circuit for said electromagnet including an engine operated switch.

5. In a fuel injection apparatus for internal combustion engines having a plunger fuel pump, the combination of a hydraulic motor actuator for the plunger of said pump, means for supplying hydraulic pressure fluid to said motor at any pressure needed to produce the desired injection pressure, and a variable throttling restriction means for controlling said motor so as to move said fuel pump plunger at any desired rate.
